UNITED STATES PATENT OFFICE.

ADOLPH C. CLARK AND THOMAS J. CLARK, OF PERTH AMBOY, NEW JERSEY.

APPARATUS FOR CASTING METALS.

No. 818,076.

Specification of Letters Patent.

Patented April 17, 1906.

Application filed December 12, 1905. Serial No. 291,409.

To all whom it may concern:

Be it known that we, ADOLPH C. CLARK and THOMAS J. CLARK, residing at Perth Amboy, in the county of Middlesex and State of New Jersey, have jointly invented certain new and useful Improvements in Apparatus for Casting Metal and Especially Copper in Molds, of which the following is a specification.

10 It consists in the arrangement and combination of parts as set forth in the below specification and specifically pointed out in the claims at the end hereof.

One of the objects of our invention is to 15 produce a simple, quickly-operated, efficient, and durable apparatus.

Another object is to produce an apparatus by which the molten metal may be poured longitudinally of the molds, and thereby avoid 20 the production of fins on the casting, which have heretofore had to be removed at considerable expense.

Another object is to produce an apparatus in which the molds may be quickly and 25 easily removed and different molds may be inserted by the use of adjustable means in which the mold is supported.

Other objects will appear from the herein-after description.

30 Referring now to the drawings, in which the same reference character indicates the same part in the different views, Figure 1 is a plan view of the apparatus. Fig. 2 is a section on line 2 of Fig. 1, showing the ladle and 35 its tilting apparatus in side elevation. Fig.

40 3 is a detail view of one form of device for dumping the mold. Fig. 4 is a detail view showing one form of the device for righting the mold. Fig. 5 is a detail view showing 45

another and our preferred device for dumping the mold. Fig. 6 shows the corresponding device for righting the mold. Fig. 7 is a section on line 7 of Figs. 1 and 2, on an enlarged scale, showing the adjustable support 50

in which is pivoted one end of the mold. Fig. 8 is a plan view of the device, on an enlarged scale, to be secured to one end of the mold for turning and righting the same. Fig. 9 is a side view of said device. Fig. 10 is a plan 55

view of the mold on a smaller scale than Figs. 7, 8, and 9. Fig. 11 is a cross-section of the mold on line 11 of Fig. 10.

On the drawings, the part marked 1 represents the foundation or base of the apparatus,

which consists of a circular plate having a 55 groove 1^a in the upper surface thereof.

2 is a circular carrier which consists of a bottom plate 2^a, which is circular in shape and is located directly over the base 1, and a plate 2^b, projecting upwardly from the middle of the circular bottom plate 2^a, dividing this bottom plate into an inner and an outer flange 2^c 2^d. The under side of the bottom plate 2^a has a groove 2^e, corresponding with and directly over the groove 1^a. 60

65 3 represents antifriction - balls in the grooves, which support and on which the carrier 2 is moved.

The carrier may be operated by any suitable means to cause the arms to move the 70 molds underneath the ladle, which is provided with separate spouts to cause the stream of molten metal to be poured in the proper manner, all of which will be herein-after described. In the construction illustrated we have shown our preferred apparatus for moving the carrier, and it is as follows: On the inner projecting flange 2^d we 75

form a rack 2^f. Meshing with this rack is a beveled pinion 4, secured on the end of a 80 shaft 5, which is driven, preferably, by an electric motor 6. The motor is supported on a suitable base 7, and the shaft 5 is supported and journaled in a suitable bearing 8. Sus-

90 pended radially from the carrier are a number of arms 9, on which are secured the cross arms or beams in which the molds are pivoted. There may be any suitable number of these radial arms. We have shown only two in the drawings, and as all are exactly 95 alike a description of one will be sufficient for all. This arm consists of an upper plate 9^a and a lower plate 9^b, the lower plate being horizontal and the upper plate sloping downwardly toward its outer end which is turned 100 down and connected to the outer end of the lower plate. These plates are connected together at or near their inner ends by a substantially vertical plate 9^c. The two plates are joined together about their longitudinal 105 center by a vertical plate or web 9^d. The arm as thus formed in cross-section appears as an I-beam, as shown in Fig. 7 of the drawings. The inner end of the upper plate is turned down and over to form a hook 9^e, 110

which fits over the upper edge of the vertical plate 2^b of the carrier 2. The inner end of the lower plate 9^d is flared in two directions.

to form a shoe 9^f, which rests against the outer edge of the outwardly-projecting flange 2^d of the carrier. Secured to the outer end of this arm is a cross plate or beam 10, having 5 circular openings 10^a near each end thereof, in which is fitted one of the journals of the molds, to be hereinafter described. 11 is another cross-beam, provided with circular openings 11^b at each end thereof into which 10 the inner and circular trunnions of the molds are journaled. This cross-beam is adjustable longitudinally of the radial arm, so as to permit the molds to be readily removed and changed and molds of different lengths to be 15 used when desired. This cross-beam has a groove 11^c on the upper edge thereof, into which fits the lower plate 9^b of the radial arm 9. This cross-beam has lugs formed thereon, each lug being provided with an opening 20 therein through which extend the bolts 12. The upper end 12^a of each of these bolts is overturned and rests upon the upper surface of the lower plate 9^b and serves to support and hold the cross-beam 11 onto the radial arm. By loosening the nuts 13 on the lower 25 ends of these bolts the cross-beam may be moved longitudinally of the supporting-arm to permit the molds to be changed and molds of different lengths to be used. By tightening 30 these nuts the cross-beam may be clamped and secured at any position on the radial arm. The cross-beams, as described, are adapted to support two molds; but they may be constructed to support one or more. 35 As all the molds are alike and are operated in the same manner, a description of one will be sufficient. The mold is represented on the drawings by the reference-numeral 14. The mold is provided with longitudinal 40 grooves 14^a, into which the molten metal is poured and the casting formed. 45 14^b and 14^c are trunnions secured to the end of the mold. These trunnions are placed below the center of gravity and near the bottom of the mold, so that the mold will swing inverted unless some means are provided to keep it upright, and this means will be described hereinafter. The trunnion 14^b is circular in cross-section and fits into one of the 50 circular openings 11^b in the cross-beam 11. The other trunnion 14^c is square in cross-section and is supported in the hub of the mold-tilting arms. 55 15 is that part of the mold-tilting device which is secured to one end of the mold. This device consists of a hub 15^a, having a square opening 15^b, into which fits the square trunnion 14^c of the mold. This hub fits into 60 and rotates freely in the circular opening 10^a of the cross-beam 10. 65 15^c, 15^d, and 15^e are arms radiating from the hub 15^a. Each of these arms has a finger 15^f, 15^g, and 15^h, respectively, projecting outwardly and at right angles therefrom. The molds are kept in their upright position dur-

ing a part of their travel by the fingers 15^f and 15^h resting on a track 16, which is concentric to the carrier and directly under the path of travel of the said fingers. At one end of this track and in the continuation of the 70 circular path thereof, but above its horizontal plane, are plates 17 and 18, which are inclined in the manner shown in Fig. 3. Against these inclined plates move the fingers 15^f, 15^g, and 15^h to dump the mold as the fingers 75 leave this end of the circular track. At the other end of the track in the circular path thereof, but below its horizontal plane, are two more plates 19 and 20, which are inclined, as shown in Fig. 4, to right the mold by the 80 fingers 15^f, 15^g, and 15^h moving thereon in the manner to be set forth in describing the operation of the apparatus.

In Figs. 5 and 6 we have illustrated our preferred devices for coöperating with the fingers to dump and right the molds. These two devices are marked 21 and 22 for convenience in describing the operation of the apparatus; but they are both constructed substantially alike, the one used for tilting 90 the molds being secured near the dumping end of the track 16 and above the horizontal plane thereof, with its two arms 21^a and 21^b projecting downwardly and the other secured near the righting end of the track, but below 95 the horizontal plane thereof, with its two arms 22^a and 22^b projecting upwardly. Each of these arms has a roller 21^c, 21^d, 22^c and 22^d, respectively, secured to the end thereof and in the path of travel of the fingers 15^f, 15^g, 100 and 15^h, with which the said fingers coöperate to dump and right the molds. If desired, in this construction the two devices 21 and 22 may be so placed in relation to the arms 15^c, 15^d, and 15^e that the arms themselves 105 will come in contact with the rollers to dump and right the molds, or in either construction we may dispense with the fingers and so locate the track 16, the inclines 17, 18, 19, and 20, or the devices 21 and 22 that the 110 arms themselves will coact with these parts to hold the mold in the upright position to dump and also to right the mold during the travel thereof.

23 is a ladle into which the molten metal is 115 poured from the furnace and from which it is poured into the molds. This ladle is pivotally suspended by the rods 24, the upper ends of the rods being supported in a well-known manner. (Not shown in the drawings.) The 120 mouth of the ladle is divided into spouts 25, directly over the grooves in the molds when the molds rest under the ladle, so that the metal will be poured into each groove of the ladle when the mold is tilted.

In the construction shown by the drawings, in which two molds having two casting-grooves are carried by the radial arms, the mouth is divided into four spouts by the upwardly-projecting plates 26 and a filling- 130

piece 27. It is apparent, however, that if a mold with only two grooves be used the ladle will be constructed so as to have only two spouts. Any means may be used for tilting the ladle; but we prefer to use a hydraulic-operated engine 28. To the piston-rod 29 of this engine is connected the links 30, which are connected to the hooks 31, secured to the outer end of the ladle. 32 is a pipe leading to this engine. The other end of the pipe has secured thereto a T connection 33, in which operates a three-way valve 34. Connected to this valve are inlet and exit pipes 35 and 36. The valve is controlled by a lever 37. By turning the three-way valve in one direction the piston-rod 29 is drawn up and tilts the ladle to pour the molten metal into the mold, and by turning the three-way valve in the opposite direction the piston-rod is caused to move down to permit the ladle to be righted.

38 is a platform or other suitable means on which the operator stands to control the three-way valve. This stand is placed adjacent to the track 16 and at a convenient distance for the operator to observe the operation of pouring the metal. Secured on this stand is a switchboard 39, by which the operator also controls the current by which the motor 6 is operated to turn the carrier.

40, 41, and 42 are the conducting-wires leading from the motor to the terminals 43, 44, and 45, respectively.

The operation of the device is as follows:

35 Suppose the parts to be in the position shown in Fig. 1 of the drawings—that is, with two of the molds righted and directly under the spout of the ladle and with the fingers 15^f and 15^h on the track 16 and with the opposite molds inverted, as shown in Figs. 1 and 2 of the drawings. Assuming that the ladle has been filled with molten metal which has been supplied thereto from a furnace (not shown) through the spout 46, the operator on 40 the platform 38 turns the valve 34 to cause the engine 28 to tilt the ladle, so that the metal will flow through the spouts 25 into the grooves or channels 14^a in the molds. When the molds are filled, the operator then turns 45 the valve 34 to right the ladle. The operator next turns the electric switch 39 to the proper terminal to put the motor 6 in operation to cause the carrier to turn on its bearings in the direction indicated by the arrow in Fig. 1, causing the molds to travel side-wise in a circle. During the travel of the filled molds they are kept upright by the fingers 15^f and 15^h, resting on the track 16. When these molds get beyond the extreme 50 right-hand end of the track, which is termed the "dumping end," as shown in Fig. 1 of the drawings, the finger 15^h strikes against the under surface of the inclined plate 17, as shown in the first position to the right of Fig. 53. As the carrier continues to move, carry-

ing the molds with it, this finger moving down on this inclined surface will cause the mold to turn to the right, and the finger 15^f will then strike against the under side of the inclined plate 18, near its upper end, and the finger 15^g will be at the lower end of the plate 17, all as shown by dotted lines in the second position of Fig. 3. A further travel of the carrier will cause the finger 15^f to move down the inclined plate 18 and completely invert the mold, as shown in the dotted position on the left of Fig. 3. When the mold is in this position, the castings will fall therefrom. The molds may then be subjected to a spray of water from pipes. (Not shown.) After 80 this the molds are coated with bone-ash by means of an air-brush. As the carrier continues to turn to the right the molds, which have been inverted, will be righted in the following manner by the inclined plates at the 85 opposite end of the track. When the inverted mold comes opposite the inclined plate 19, the finger 15^h comes in contact with the upper surface of this plate, and as the carrier continues to swing the mold to the right this 90 finger bearing upon this inclined plate will turn the mold to the left, and as the carrier continues to travel the finger 15^g comes in contact with the upper surface of the inclined plate 20, when the finger 15^h is at the upper 95 end of the inclined plate 19, as shown by the dotted lines in the second position in Fig. 4. As the carrier still continues to travel the finger 15^g travels up the inclined plate 20 and turns the mold to the left until it is righted, 100 as shown in the dotted position to the left of Fig. 4. The carrier continues to travel until it brings the mold directly under the mouth of the ladle, as shown in Figs. 1 and 2, when the operator stops the motor and tilts the ladle to again fill the mold, as described before. 105 As the trunnions are placed on the molds below the center of gravity thereof when inverted, as shown in the position to the left of Fig. 3, they will remain so during their travel 110 from the dumping end to the righting end of the track without any steadyng means. 115 In the construction shown in Fig. 5 the fingers 15^f, 15^g, and 15^h come in contact with the rollers 21^c and 21^d, causing the molds to 120 be inverted and dumped, as clearly shown in said Fig. 5. When the molds have been swung to the righting end of the track, these fingers come in contact with the rollers 22^c and 22^d and the mold is righted, as clearly 125 shown in Fig. 6, and which, we believe, needs no further description, as it is apparent that the rollers take the place of the inclined plates to coöperate with the fingers to dump and right the molds. In this preferred form 130 when the devices 21 and 22 are so located that the rollers 21^c 21^d and 22^c 22^d are in the path of the arms 15^c 15^d 15^e these arms instead of the fingers will coat with the rollers, as is apparent from the description above, to 135

dump and right the molds during their circular travel. Of course it is also understood that when the track and the dumping and righting means, as shown in Figs. 1 and 2 of the drawings, are so placed in relation to the arms that the arms themselves will coact with these parts the fingers in that case may be omitted.

In the former constructions of apparatus of the class to which our invention belongs the molds were moved by the carrier in the direction of its length, which caused a surging of the molten metal which would splash against the ends of the molds, causing a chilling of the copper and the production of a fin on the casting. If this fin was not removed, which had to be done at considerable expense, the copper casting could not be used for drawing into wire of high reliable electric conductivity, for the reason that the fine edges would cause faults that could only be removed by cutting out the imperfect section and splicing the wire. In our construction of apparatus in which the molds are placed lengthwise or longitudinally of the ladle and in pairs substantially parallel to each other, as shown, instead of being placed in radial line from the center of the apparatus or carrier and in which the molds travel sidewise in moving from the ladle to the dumping position there is no tendency of the metal to surge over the edges of the molds to cause fins, and on this account the carrier can be moved at greater rapidity, as the tendency of the splash decreases in direction proportionate to the length of the mold in the direction of its travel. Furthermore, by arranging the molds and ladle as we have done we are able to pour about four times the amount of metal in a given time than has heretofore been done by prior apparatus. All this reduces the cost and increases the efficiency of the apparatus. Not only this, it will be seen that in our apparatus the number of working parts has been decreased and the apparatus itself can be built at less expense than prior apparatus. Furthermore, we have placed the operator's platform away and disconnected from the carrier and in such position that he can more readily observe the ladle and the operation of pouring the metal and can see and have full control over the operation of the carrier.

As many changes could be made in the above construction and many apparently widely different embodiments of our invention could be made without departing from the scope thereof, we intend that all matter contained in the above description or shown in the accompanying drawings shall be interpreted as illustrative and not in a limiting sense. We desire it also to be understood that the language used in the following claims is intended to cover all of the generic and specific features of the invention herein

described and all statements of the scope of the invention which, as a matter of language, might be said to fall therebetween.

Having now described our invention, what we claim as new, and desire to secure by Letters Patent, is—

1. In a casting-machine, a circular carrier, means for rotating the same, means extending radially from and carried by the carrier to support a mold, a mold pivotally supported by said means, fingers connected to the mold, a track forming part of a circle on which the fingers rest and by which the mold is held in an upright position during part of the travel of the carrier, means adjacent to one end of the track against which the fingers contact and by which the mold is inverted, and means adjacent to the other end of the track against which the fingers contact to right the mold and place the fingers in position to rest on the track.

2. In a casting-machine, a circular carrier, means for rotating the same, means extending radially from and carried by the carrier to support a mold, a mold pivotally supported by said means, fingers connected to the mold, a track forming part of a circle on which the fingers rest and by which the mold is held in an upright position during part of the travel of the carrier, and a plate adjacent to one end of the track, said plate having downwardly-projecting arms and rollers carried by the arms against which the fingers contact and by which the mold is inverted.

3. In a casting-machine, a circular carrier, means for rotating the same, means extending radially from and carried by the carrier to support a mold, a mold pivotally supported by said means, fingers connected to the mold, a track forming part of a circle on which the fingers rest and by which the mold is held in an upright position during part of the travel of the carrier, a plate adjacent to one end of the track, said plate having downwardly-projecting arms and rollers carried by the arms against which the fingers contact and by which the mold is inverted, and another plate adjacent to the other end of the track, having arms projecting vertically and rollers carried by the arms against which the fingers contact to right the mold and to place the fingers in position to rest upon the track to hold the mold in its upright position.

4. In a casting-machine, a carrier, an arm extending radially therefrom and supported thereby, a beam having an opening therein secured to the outer end of the arm, another beam having an opening therein secured to the arm between the ends thereof, bolts carried by the beam and coacting with the arm, whereby the said beam may be adjustable lengthwise of the arm and set at any predetermined point thereon, and a plurality of molds pivoted in the openings in the beams.

5. In a casting-machine, a circular carrier,

means for rotating the carrier, an arm extending radially from the carrier, a cross-beam secured to the end of the arm, having a circular opening thereon, another cross-beam between the ends of the arm and adjustable longitudinally thereon, a mold pivoted in said beams, a hub secured to one end of the mold, arms radiating from the hub and fingers extending from the arms, means coacting with said fingers to invert the mold, a track forming part of a circle, means near one end of the track coöperating with said fingers to invert the mold, and means adjacent to the other end of the track to right the mold, said fingers resting on the track during a part of the travel of the carrier to hold the mold in its upright position.

6. In a casting-machine, a circular carrier, means for operating the same, an arm extending radially from and supported by the carrier, a cross-beam having an opening therein secured to one end of the arm, another cross-beam having an opening therein between the ends of the arm, means for adjustably supporting the second cross-beam longitudinally of the arm, a mold having trunnions supported in said openings, a hub secured to one of the trunnions, arms extending radially from said hub, fingers extending outwardly from the ends of the arms, a track forming part of a circle and on which the fingers rest to hold the mold in an upright position, a plate above the track and adjacent to one end thereof, arms extending downwardly from said plate, rollers carried by said arms against which the fingers contact to invert the mold, another plate below the mold and adjacent to the other end thereof, said plate having arms extending upwardly, and rollers carried by said arms against which the fingers contact to right the mold and place the fingers in position to rest on the track to hold the mold in its upright position.

7. In a casting-machine, a carrier, means for moving the same, means carried thereby to support a mold, a mold pivotally supported by said means, arms connected to the mold, fingers extending from the arms, a track on which the fingers rest and by which the mold is held in an upright position during a part of the travel thereof, a plate adjacent to one end of the track, said plate having downwardly-projecting arms, rollers carried by the arms against which the first-mentioned arms contact and by which the mold is inverted, and another plate adjacent to the other end of the track having upwardly-projecting arms, rollers carried by these arms against which the arms secured to the mold coact to right the mold and place the fingers in position to rest upon the track and to hold the mold in an upright position.

8. In a casting-machine, a carrier, means for moving the same, means carried thereby for supporting a mold, a mold pivotally sup-

ported by said means, arms connected to the mold, a track on which the arms rest and by which the mold is held in an upright position during a part of the travel thereof, a plate adjacent to one end of the arm, said plate having downwardly-projecting arms, a roller carried by each of the arms against which the arms of the mold contact to invert the mold, and another plate adjacent to the other end of the track having vertically-projecting arms, and rollers carried by each of said arms against which the arms of the mold contact to right the mold and to place the arms of the mold in such position as to rest upon the track and to hold the mold in its upright position during the further travel of the mold.

9. In a casting-machine, a circular carrier, means for rotating the carrier, an arm extending radially from the carrier, an adjustable cross-beam secured to the same between its ends, another cross-beam secured at the outer end of the arm, a plurality of molds pivoted in said beams, a hub connected to one end of each mold, arms radiating from the hubs and means coacting with said arms to invert the molds during the travel of the carrier.

10. In a casting-machine, a carrier, an arm extending radially therefrom and supported thereby, a pair of longitudinal molds pivotally supported on each side of the said arm, said molds being parallel to each other, arms radiating from the outer end of the molds, a track forming part of a circle, means near one end of the track coöperating with said arms to invert the molds, and means adjacent to the other end of the track to right the molds, the said arms resting on the track during a part of the travel thereof to hold the molds in an upright position.

11. In a casting-machine, a carrier, an arm extending radially therefrom and supported thereby, a cross-beam having a circular opening in each end thereof, secured to the outer end of the arm, another cross-beam having a circular opening in each end thereof, secured to the said arm between its ends, said second beam being adjustable lengthwise of the arm, a pair of molds pivoted in the openings in the said cross-beams, said molds being located one on each side of the arm and being parallel to each other, means for operating the carrier, means for inverting the molds at a predetermined point in their travel, and separate means for righting the molds.

In witness whereof we have hereunto set our hands, at Perth Amboy, county of Middlesex, and State of New Jersey, this 9th day of December, 1905.

ADOLPH C. CLARK.
THOMAS J. CLARK.

In presence of—

PERCY ROTHWELL,
CHARLES C. HOMMANN.
